(57) **CLAIM**

The ornamental design for a deadbolt knob assembly, as shown and described.

DESCRIPTION

FIG. 1 is a perspective view, taken from the front, top and right side, of a deadbolt knob assembly showing our new design;

FIG. 2 is a front elevational view of the deadbolt knob assembly shown in FIG. 1;

FIG. 3 is a right side elevational view of the deadbolt knob assembly shown in FIG. 1, the left side elevational view being identical thereto;

FIG. 4 is a bottom plan view of the deadbolt knob assembly shown in FIG. 1;

FIG. 5 is a rear elevational view of the deadbolt knob assembly shown in FIG. 1; and,

FIG. 6 is a top plan view of the deadbolt knob assembly shown in FIG. 1.

The broken lines illustrate environmental structure which forms no part of the claimed design.
